(57) **CLAIM**

The ornamental design for a cable tray cable drop component of a cable management solution for building construction, as shown and described.

DESCRIPTION

FIG. 1 is a front perspective view of a cable tray cable drop component of a cable management solution for building construction.

FIG. 2 is a front elevational view of the component shown in FIG. 1.

FIG. 3 is a rear elevational view of the component shown in FIG. 1.

FIG. 4 is a top plan view of the component shown in FIG. 1.

FIG. 5 is a bottom plan view of the component shown in FIG. 1.

FIG. 6 is a right side elevational view of the component shown in FIG. 1; and,

FIG. 7 is a left side elevational view of the component shown in FIG. 1.

1 Claim, 5 Drawing Sheets
